(57) **CLAIM**

The ornamental design for a selfie stick, as shown and described.

DESCRIPTION

FIG. 1 is a front perspective view of a selfie stick, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the selfie stick in a use state thereof;

FIG. 10 is a front perspective view showing the selfie stick in an expanded state thereof;

FIG. 11 is an enlarged detail view of area 11 in FIG. 1 thereof;

FIG. 12 is an enlarged detail view of area 12 in FIG. 2 thereof; and,

FIG. 13 is an enlarged detail view of area 13 in FIG. 10. The broken lines in the drawings illustrate the portions of the selfie stick, which form no part of the claimed design. The dash-dot-dash broken lines encircling the enlarged views are for annotative purposes only and form no part of the claim thereof.

1 Claim, 13 Drawing Sheets
